[57] CLAIM

The ornamental design for a cutting board, as shown and
described.

DESCRIPTION

FIG. 1 is a top, front and left side perspective view of a
cutting board showing my new design;

FIG. 2 is an exploded top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.

The broken line showing of a knife and hot dogs are for
illustrative purposes only and form no part of the claimed
design.
